DESIGN FOR A BOOK END

Robert D. Barrett, New York, N. Y.

Application May 23, 1933. Serial No. 48,196

Term of patent 7 years

To all whom it may concern:

Be it known that I, ROBERT D. BARRETT, a citizen of the United States and a resident of the city of New York (borough of Manhattan), in the county of New York and State of New York, have invented the new, original, and ornamental Design for a Book End, of which the following is a specification.

Reference is had to the accompanying drawing forming part hereof, wherein—

I claim:

The ornamental design for a book end, substantially as shown.

ROBERT D. BARRETT.
